J. SOSS.

LOCK CONSTRUCTION.

APPLICATION FILED SEPT. 14, 1920.

1,402,104.

Patented Jan. 3, 1922.

UNITED STATES PATENT OFFICE.

JOSEPH SOSS, OF NEW YORK, N. Y.

LOCK CONSTRUCTION.

1,402,104.

Specification of Letters Patent. Patented Jan. 3, 1922.

Application filed September 14, 1920. Serial No. 410,239.

To all whom it may concern:

Be it known that I, JOSEPH Soss, a citizen of the United States, and residing at New York, in the county of New York and State 5 of New York, have invented certain new and useful Improvements in Lock Constructions, of which the following is a specification, such as will enable those skilled in the art to which it appertains to make and use the 10 same.

This invention relates to lock constructions and particularly to what are known as knob locks and especially to locks of this class designed for use in connection with the 15 doors of motor vehicles, and the object of this invention is to provide a lock of the class and for the purpose specified with improved means for locking the knob or handle of a door against movement to prevent the 20 opening of the door, said means cooperating with the usual latch bolt of the door; and with this and other objects in view the invention consists in a lock construction of the 25 class and for the purpose specified which is simple in construction and operation and efficient in use, and which is constructed and operated as hereinafter described and claimed.

The invention is fully disclosed in the following specification, of which the accompanying drawing forms a part, in which the 30 separate parts of my improvement are designated by suitable reference characters in each of the views, and in which:—

Fig. 1 is a side view of a part of a door with a knob or handle mounted in connection therewith and showing my improved lock construction;

Fig. 2 a view looking in the direction of 40 the arrow 2 of Fig. 1 with part of the construction broken away and in section;

Fig. 3 a partial section on the line 3—3 of Fig. 2 and on an enlarged scale;

Fig. 4 a view similar to Fig. 2 with parts 45 of the construction in a different position;

Fig. 5 a partial section on the line 5—5 of Fig. 4 and on a reduced scale; and,

Fig. 6 a partial section on the line 6—6 of Fig. 3 and on a reduced scale.

In Figs. 1 and 2 of the drawing I have indicated at 10 part of a door, preferably a motor vehicle door, in which is mounted the usual latch bolt 11 operated through a knob or handle 12 in the usual manner.

The knob or handle 12 in the construction shown comprises a main body portion 13

provided at its outer end with a downwardly directed hand-piece 14. The inner end of the body portion 13 is provided with a square shank 15 which operates the latch bolt 11. 60

The body portion 13 is provided with a bore 16 which opens outwardly through the end of said body portion and the inner end of the body portion is reduced as shown at 17 and passes through a retaining collar 18 65 secured to the face of the door 10 by screws or other devices 19. The collar 18 is provided on its inner face with four oppositely directed apertures or recesses 20.

Mounted in and movable radially of the 70 body portion 13, or the reduced end 17 thereof, are two lock bolts 21 which are normally contained within the body portion but which are adapted to be projected into two of the oppositely extended apertures 20 in the retaining collar 18. Two levers 22 are pivoted 75 within the body portion 13 as shown at 23, and one end portion of said levers pass into and are adapted to operate in apertures 24 in the abutting ends of the lock bolts 21, and 80 links 25 are pivoted to the other end portions of said levers as shown at 26. The other ends of said links are pivoted to a movable sleeve 27 as shown at 28.

The inner end portion of the bore 16 is 85 reduced and is provided with two key-ways 29 in which projecting lugs 30 on the sleeve 27 operate to prevent the rotation of said sleeve in the body portion 13 but permitting 90 of the longitudinal movement of said sleeve therein.

A disk 31 is mounted within the bore 16 outwardly of the sleeve 27 and provided with an inwardly directed reduced and threaded stud 32, and the sleeve 27 is correspondingly threaded so that when the disk 31 is rotated the sleeve 27 will be moved 95 longitudinally of the body portion 13.

A plug 33 is mounted in the bore 16 outwardly of the disk 31 and retained in position by a pin 34 passed through the body portion 13 and engaging an annular groove 35 in the periphery of the plug 33. The outer end portion of the disk 31 is provided with a projection 36 provided with two key 100 receiving notches or recesses 37, and the inner end of the plug 33 is recessed to receive the projection 36 and said plug is provided centrally with a key aperture 38 through which a key 39 may be passed to bring projecting members 40 thereof into engagement 105 with the recesses 37 of the disk 31 to permit 110

of the rotation of said disk, and the movement of the lock bolts 21, through the levers 22 and links 25 as well as the sleeve 27. The disk 31 is held in position by the plug 33 and the shoulder formed by the reduced bore of the body portion.

The operation of my improved lock construction will be readily understood from the foregoing description when taken in connection with the accompanying drawing and the following statement. It will be apparent that the lock bolts 21 are retained against displacement in the body portion 13 by the levers 22, links 25 and the sleeve 27, and the levers, links and said sleeve as well as the disk 31 are retained against displacement in the body portion by the plug 33. After the parts have all been assembled in the manner shown and assuming the lock to be in its inoperative position as shown in Fig. 3, the same may be moved into operative position by inserting the key 39 into the aperture 38 of the plug 33 and rotating said key to bring the projections 40 thereof into alignment with the recesses 37 in the disk 31, after which the key 39 is rotated to move the sleeve 27 inwardly into the position shown in Fig. 4, which operation will move the lock bolts 21 radially into two of the apertures 20 in the retaining sleeve 18 through the links 25 and levers 22. When the lock bolts 21 are in their operative position the latch bolt 11 as well as the knob or handle 12 are locked against movement and the door 10 cannot be opened by reason of the connection of the square shank 15 of the belt 11. By inserting the key 39 the various parts of the lock mechanism may be returned to their inoperative position by rotating said key in the opposite direction to move the sleeve 27 outwardly, which operation will return the bolts 21 into the position shown in Fig. 3. It will be noted that the outer ends of the bolts 21 are slightly curved as shown at 41 in Fig. 5 of the drawing to correspond with the periphery of the reduced end 17 of the body portion 13.

It will be understood that I am not necessarily limited to the link and lever construction herein shown and described, nor to the specific means shown for actuating said link and lever construction, or for moving the lock bolts 21 radially, and various changes in and modifications of the construction herein shown and described may be made, within the scope of the appended claims, without departing from the spirit of my invention or sacrificing its advantages.

Having fully described my invention, what I claim as new and desire to secure by Letters Patent, is:—

1. A lock construction of the class described comprising a plurality of lock bolts mounted to move radially in a suitable support, key-operated means mounted in said

support and adapted to move said lock bolts radially, said means comprising a sleeve movable longitudinally of the support, and levers cooperating with said lock bolts and pivotally connected with and operated by 70 said sleeve.

2. A knob lock of the class described comprising a suitable knob body portion, a sleeve mounted to move longitudinally of the body portion, key-operated means for 75 giving said sleeve its movement, and means in operative connection with said sleeve and movable laterally of said body portion for locking the knob against rotation.

3. A knob lock for doors, said knob comprising a suitable body portion in operative connection with the usual latch bolt of a door, lock bolts movable radially in said body portion and adapted to lock said body portion against rotation when in their operative position, a sleeve mounted to move longitudinally of the body portion, key-operated means for giving said sleeve its movement, and means connected with said sleeve and in operative connection with said bolts 85 for moving said bolts radially in the movement of said sleeve.

4. A knob lock for doors, said knob comprising a suitable body portion in operative connection with the usual latch bolt of a 95 door, lock bolts movable radially in said body portion and adapted to lock said body portion against rotation when in their operative position, a sleeve mounted to move longitudinally of the body portion, key-operated means for giving said sleeve its movement, means connected with said sleeve and in operative connection with said bolts for moving said bolts radially in the movement 100 of said sleeve, and means for retaining said key-operated means, said sleeve and said last named means against displacement in the body portion.

5. The combination with a latch bolt of a door and a knob for operating said latch 110 bolt, of a lock construction mounted within the body portion of said knob and comprising lock bolts movable radially through said body portion, means on one side of the door in connection with which said lock bolts operate for locking said knob against rotation, a sleeve mounted in and movable longitudinally of said body portion, key-operated means for giving said sleeve its movement, and means connected with said sleeve and 115 in operative connection with said bolts for moving said bolts radially in the movement 120 of said sleeve.

6. The combination with a latch bolt of a door and a knob for operating said latch 125 bolt, of a lock construction mounted within the body portion of said knob and comprising lock bolts movable radially through said body portion, means on one side of the door in connection with which said lock bolts op- 130

erate for locking said knob against rotation, a sleeve mounted in and movable longitudinally of said body portion, key-operated means for giving said sleeve its movement, 5 means connected with said sleeve and in operative connection with said bolts for moving said bolts radially in the movement of said sleeve, and means for retaining the various parts of the lock construction within 10 said body portion.

7. A lock construction of the class described comprising a plurality of lock bolts mounted to move radially in a suitable support, a sleeve mounted to move longitudinally of said support, key-operated means for giving said sleeve its movement, levers pivotally mounted in said support and in operative connection with said lock bolts, and links mounted in connection with said 15 20 sleeve and said levers whereby the move-

ment of said sleeve will cause said lock bolts to be moved radially of said levers and links.

8. A lock construction of the class described comprising a plurality of lock bolts mounted to move radially in a suitable support, 25 a key-operated sleeve mounted in said support and movable longitudinally thereof, and means on said sleeve and in operative connection with said bolts for moving said bolts radially in the movement of said 30 sleeve.

In testimony that I claim the foregoing as my invention I have signed my name in presence of the subscribing witnesses this 13th day of September, 1920.

JOSEPH SOSS.
